SCANNING DEVICE

Garrett Vander Veer Dillenback, Jr., Slingerlands,
N. Y., assignor, by mesne assignments, to Radio
Corporation of America, a corporation of Dela-
ware

Application October 9, 1930, Serial No. 487,433

2 Claims. (Cl. 178—69.5)

This invention relates to electro-optical systems, and with particularity to methods and means for controlling the speed of analyzing and integrating mechanisms.

8 While the invention is of peculiar adaptability to such systems as picture transmission, television or the like, it will be understood that the invention in its broad aspects is not limited to any particular system, but is capable of use in 10 any situation where a commercial supply is available for furnishing the main driving power to the mechanism to be synchronized and an additional source of constant frequency currents are available for controlling accurate speed of the 15 mechanism.

The invention is in the nature of an improvement upon the system disclosed in applications Serial Nos. 365,818 and 405,354.

One of the principal objects of the invention 20 is to provide a method of synchronizing transmitter and receiving apparatus such as ordinarily employed in television, picture transmission and similar systems.

25 Another object of the invention is to provide a system for transmitting and/or reproducing images, visual representations or the like employing a single channel for carrying both the synchronizing and image or picture signals.

Another object of the invention is to provide 30 methods and means for enabling the picture or image currents themselves to be utilized in controlling the synchronism of receiving and transmitting apparatus in television, picture transmission or similar systems.

35 A feature of the invention relates to a novel drive for rotatable members generally, comprising a variable speed motor, and a synchronous motor, both these motors being relatively simple and cheap to construct.

40 Another feature of the invention relates to a driving mechanism for a member adapted to be moved at an extremely constant rate of speed comprising an eddy current motor and a synchronizing motor.

45 Another feature of the invention relates to methods and means for operating an analyzing or synthesizing device such as ordinarily employed in image or picture transmission systems. In accordance with this feature the driving mechanism for the devices is divided into two portions, one adapted to be energized by current derived from a commercial supply and the other adapted to be energized by currents having characteristics corresponding to the speed of a transmitter or a 50 receiver.

A further feature relates to a novel form of synchronizing drive wherein the rotor member is coupled for relative movement to the driving shaft, and is adapted to be energized under control of synchronizing currents.

A still further feature relates to the novel organization and arrangement of elements which go to make up a simple, cheap, economical and highly accurate television or image reproducing apparatus wherein the image currents themselves are used for synchronizing. 65

In the drawing Fig. 1 shows in schematic form a system embodying features of the invention;

Figure 2 is a detail view of a modified form of synchronizing device that may be used in the 70 system of Fig. 1;

Fig. 3 is an end view of the synchronizing device of Fig. 2.

Referring more particularly to Fig. 1, the numeral 1 represents a scanning device of known 75 construction. This device may take the form of a drum or disc. Thus in Fig. 1 the scanning device is in the form of a thin annular strip of metal, fibre or any other light material provided with a convolution or convolutions of circumferentially 80 spaced scanning elements or openings in the manner well known in the television art. The annular member 1 is fastened in any suitable manner to a circular metal disc 2 of copper, aluminum or other metal suitable for use as the rotor 85 of an eddy current motor. The disc 2 is fastened to a shaft 3 provided with suitable anti-frictional bearings in standards (not shown). Mounted adjacent the opposite faces of the disc 2 are field magnets 4, 5 and 6. Each of the magnets 4, 5 and 90 6 is adapted to be energized by alternating or pulsating current from a suitable source 7. Thus the source 7 may take the form of commercial alternating supply means, the frequency of which may vary within the usual limits found in such 95 commercial systems. The currents in the windings 4, 5 and 6 are displaced in phase in any manner known to the art, for example by inserting a reactance such as a condenser 8 in the circuit of the magnets 5 or 6. It will be understood 100 of course that this reactance may be variable and may be placed in circuit with the magnet 4 if desired. A suitable rheostat 10 is connected in circuit with the magnets and the source 7 to control the asynchronous speed of the disc 2. The devices 2, 4, 5 and 6 thus form in effect a variable speed motor of the eddy current type, the asynchronous speed of which may be controlled by means of the current control device 10.

Mounted adjacent the scanning member 1 is

a suitable light translating device 11 which may take the form of a neon lamp provided with a suitable adjustable mask to illuminate the scanning field of the member 1.

5 For a detail description of this portion of the apparatus, reference may be had to the application of G. V. Dillenback, Jr., Serial No. 453,890. Removably attached to one end of the shaft 3 is a synchronizing rotor 12 in the form of a toothed 10 wheel such as ordinarily employed in LaCour or Phonic wheel motors. Mounted adjacent the wheel 12 is a field magnet 13 provided with a winding 14 adapted to be energized by currents received from the transmitting station.

15 As described in detail in application Serial No. 365,818, and as now well known in television systems, the image or picture currents have a characteristic frequency which is determined by the speed of the scanning mechanism at the transmitter. Thus if a motion picture film is being scanned at the rate of 15 pictures per second and the scanning device is provided with 48 scanning elements, then the picture currents in addition to being modulated according to the image characteristics also have an inherent characteristic of 720 cycles per second.

20 In accordance with the present invention it is proposed to employ this characteristic frequency to energize the field 13. Thus as illustrated in Fig. 1, the numeral 15 represents a transmitting 25 station of known construction capable of transmitting image or picture currents having a characteristic frequency related to the speed of the transmitting analyzer. The numeral 16 represents any suitable transmission channel such as a radio or wired lined channel. In the case of radio transmission the channel 16 feeds into a suitable detecting or demodulating apparatus 17. The output of the device 17 is further amplified 30 in a suitable amplifier 18 and applied to the reproducing device 11.

40 Another portion of the output passes through a filter 19 and is amplified in the device 20. The amplified filtered output is then impressed upon the winding 14 and controls the synchronous speed of the member 12 and consequently of the shaft 3. In the case above assumed, namely with 48 45 lines per picture, 15 pictures per second the output of the device 17 will have a characteristic component of 720 cycles per second and preferably, therefore, the device 19 may be an electrical network designed to pass currents having a frequency in the neighborhood of 720 cycles per second. Furthermore, if desired the amplifier 20 may be 50 a tuned amplifier having its maximum transmitting efficiency in the range of 720 cycles per second.

55 From the foregoing description it will be seen that the main driving power for the device 1 is derived from the commercial supply 7 through the intermediary of the members 2, 4, 5 and 6, while the synchronous speed thereof is controlled by the device 12. It will be obvious therefore that if the transmitter or analyzing mechanism should 60 vary in speed that the characteristic picture frequency will also vary and consequently the device 1 will be kept continuously in step with the transmitter. It will be obvious that the filter 19 and the amplifier 20 may be made adjustable if desired, so as to allow for the variation range 65 of the transmitter. If the receiving apparatus shown in Fig. 1 is to be synchronized at a different frequency then the synchronizing rotor 12 will be replaced with a rotor corresponding to 70 the synchronizing frequency and similarly the

members 19 and 20 will be adjusted or replaced by the corresponding networks.

75 While the invention is described above as applied to one known type of television system, it will be understood that the invention is not limited thereto. Thus for example the characteristic frequency or modulation of the picture frequencies may be produced in the manner described in Patent 1,694,065 to C. F. Jenkins, granted December 4, 1928. It has been found that the driving shaft 3 may be brought into synchronization more expeditiously and maintained in synchronization over a relatively wide synchronizing frequency range if the synchronizing rotor 12 is resiliently coupled to the shaft 3.

80 Thus as shown in Fig. 2 the shaft 3 is provided with a threaded end to receive a shoulder screw 21. The synchronizing rotor 12 is mounted loosely for rotation on the shoulder end of the screw 21 and is coupled to the shaft 3 by a coil spring 22. It has been found that this type of coupling between the rotor and shaft is necessary where the transmitting apparatus and the synchronizing currents vary over a comparatively wide range. It will be obvious, of course, that the manner of coupling the rotor 12 to shaft 3 as shown in Figs. 2 and 3 is merely illustrative, and that any other equivalent resilient connection between the rotor and shaft may be provided.

85 While specific apparatus and arrangements 10 have been described hereinabove, it will be understood that the invention is not limited thereto, since broadly the invention is capable of use in any situation where the main driving power for a driving member is derived from commercial 11 supply mains and the member is synchronized by currents transmitted from a distance.

90 Changes and modifications other than those hereinabove mentioned may be made without departing from the spirit and scope of the invention. 11 For example, while an ordinary or undamped spring coupling is provided between shaft 3 and rotor 12, it is preferred, particularly where there is very little friction in the bearing, to provide additional damping means for the free vibrations of the spring. Any well known means for dampening the free vibrations of the spring coupling may be employed, for example hydraulic or mechanical friction members may be employed.

95 It is also contemplated to employ a coupling 12 of the type ordinarily referred to in the printing telegraph art with a mercury flywheel coupling, in which case the spring coupling may be eliminated entirely, or reliance may be placed, if desired, upon both the spring coupling and the 13 mercury flywheel.

100 It will also be obvious from the foregoing disclosure that instead of providing the flexible or resilient coupling between the synchronizing rotor and the shaft, the said rotor may be rigidly fastened to the shaft and the resilient coupling provided between the scanning disc and its shaft.

105 What is claimed is:

110 1. In a device of the character described the 140 combination of a driven shaft, a television scanning device attached at one end of said shaft and having a portion serving as the rotor of an eddy current motor, means for driving said shaft and device by eddy current action on said portion 145 of said disc, said shaft being threaded at its other and free end, a shoulder screw adapted to be threaded into said threaded free end of said shaft, a synchronizing rotor loosely mounted for rotation on the shoulder end of said screw, and a 150

resilient member for coupling together said synchronizing rotor and said shaft.

a member adapted to be threaded into the threaded end of said shaft, a synchronizing rotor loosely mounted on said member for rotation thereon, and a spring having one end thereof secured to said rotor and the other end thereof secured to said shaft for coupling said rotor and shaft together.

2. In a device of the character described the combination of a driven shaft having an end thereof internally threaded, a television scanning device attached to said shaft and having a portion serving as the rotor of an eddy current motor, means for driving said shaft and device by eddy current action on said portion of said disc.
